UNITED STATES PATENT OFFICE.

THOMAS E. O'BRIEN, OF WATERTOWN, MASSACHUSETTS.

DESIGN FOR A GROOVING-TOOL BLANK.

SPECIFICATION forming part of Design No. 30,671, dated May 2, 1899.

Application filed March 17, 1899. Serial No. 709,554. Term of patent 14 years.

To all whom it may concern:

Be it known that I, THOMAS E. O'BRIEN, of Watertown, in the county of Middlesex and State of Massachusetts, have invented and produced a certain new and original Design 5 for a Grooving-Tool Blank, of which the following is a specification, reference being had to the accompanying drawings, forming a part thereof.

Figure 1 is a top plan view of a blank, showing my new design. Fig. 2 is a perspective view of the same.

As shown in the drawings, the leading or material feature of my design consists in a 15 thin plate having flat parallel sides α α , said plate being of uniform thickness to its rear

edge, and a wedge-shaped projection b , extending along the other edge of the plate, the front wall of the projection b being in a single uniform inclined plane from the apex of the wedge to the surface of the plate opposite that from which the wedge-shaped projection rises.

I claim—

The design for a grooving-tool blank, substantially as herein shown and described.

In testimony whereof I have affixed my signature in presence of two witnesses.

THOMAS E. O'BRIEN.

Witnesses:

HORACE BROWN,
A. D. HARRISON.
